J. C. HEEREY

CURTAIN CLASP

Filed Feb. 24, 1922

FIG. 1.

FIG. 2.

FIG. 3.

FIG. 4.

James C. Heerey,
INVENTOR

Jno. Babin, Jr.
WITNESS

BY Victor J. Evans
ATTORNEY

UNITED STATES PATENT OFFICE.

JAMES C. HEEREY, OF PHILADELPHIA, PENNSYLVANIA.

CURTAIN CLASP.

Application filed February 24, 1922. Serial No. 538,833.

To all whom it may concern:

Be it known that I, JAMES C. HEEREY, a subject of the King of Great Britain and British Dominions, residing at Philadelphia, in the county of Philadelphia and State of Pennsylvania, have invented new and useful Improvements in Curtain Clasps, of which the following is a specification.

This invention relates to drapery holders and it has more particular reference to that type or form of device which is adapted for attachment to a window or door frame and thereby serves as a means for draping or holding back a curtain or screen by clasping or gripping the draped material between opposed spring jaws.

The primary object of my invention is to provide a device of the foregoing specified character which will not tear, cut or otherwise mar or damage drapery hangings to which it may be applied.

Another object of this invention is to provide a device of the nature referred to which is made of strong spring steel, which is fashioned so that when fixed in place its inherent grip is automatically increased whilst it cannot become displaced or accidentally moved from its proper position relative to the drapery it is intended to hold back.

A further object of this invention is to provide a simple, cheap and durable drapery or curtain clasp that is both effective and extremely serviceable in use.

With the foregoing and other objects in view my invention comprises what may be conveniently termed a clip-clasp in combination with a holder or attaching device that is fashioned to abut the folded over end of the clip-clasp and secure the same against lateral or other misplacement when in use.

In the further disclosure of the invention reference is to be had to the accompanying sheet of drawings constituting a part of this specification and in which like characters of reference designate the same or corresponding parts in all the views.

Figure 1—is a fragmentary view illustrative of a portion of a window frame and associated curtain having my novel holder applied thereto.

Figure 2—is a detached plan view of my novel curtain holder with its attaching means and normal attached position shown by dot-and-dash lines.

Figure 3—is a face view of the drapery holder securing means; and,

Figure 4—is a section taken substantially on the line 4—4 in the preceding figure.

Referring more particularly to the views 60 a fragmentary portion of a window case-ment is designated by the numeral 5 whilst a curtain therefor is characterized by the Figure 6.

In accordance with my invention I take 65 a strip of strong spring steel of the desired dimensions and fold the same upon itself at 7 to provide registering members 8, 9 the former of which constitutes the base or back limb while the latter has its free end 70 slightly turned or rolled at 10 so that material being passed thereunder cannot be torn or otherwise damaged. An examination of Figure 2 more particularly will disclose the fact that the turned over part 7 75 is outwardly bulged as well as rounded at 11, 11 with a smaller radius, while the aforesaid members 8, 9 are opposingly curved to-wards each other so as to normally occupy 80 and hold the position indicated by the full lines.

In order to provide a simple and effective means for securing the clip-clasp or drapery holder to a window or door frame, I preferably employ the device shown more explicitly by Figures 3 and 4, the same embracing a bridge piece 12 including flanges 13, 13 provided with countersink holes 14 for the reception of wood screws for example. Appropriately stamped up from the bridge 90 piece 12 is a tongue or abutment member 15 of substantially the same width as that of the strip of material from which the holder is made, said abutment member serving in use as will be clearly understood from the 95 dot-and-dash lines in Figure 2 as a wall or stop for the aforesaid rounded part 7. Furthermore, it will be clearly understood that when the back member 8 is passed through the slot 16—Figure 3—caused by stamping up the tongue or abutment member 15 from the front thereof that it will be drawn into close abutment or contact with the window or door frame 5 on which the device is secured. This gripping or collapsing of 100 the normally curved part of the limb 8 will obviously result in the distortion of the clip-clasp or holder to the position indicated by the dot-and-dash lines in Figure 2 with an inherent increasing of the grip be- 110

tween the members 8 and 9 as will be perfectly clear to those acquainted with the art to which this invention appertains.

In use it will be perfectly clear that the 5 drapery or curtain 5 is slipped or forced between the members 8, 9 and adjusted to give the desired artistic effect.

From the foregoing description and an examination of the drawings it will be clearly apparent that by my invention I have 10 provided an extremely simple, durable and neat article for the purposes specified.

Whilst there has been shown and described a convenient embodiment of my invention it will be readily understood that 15 the same is susceptible of minor detail changes, and the right is accordingly here-

by reserved to make such variations or modifications therein as fairly lie within the scope of the appended claim. 20

Having described my invention, what I claim as new and desire to secure by Letters Patent is:

A curtain clasp comprising a length of highly springy material folded upon itself 25 to provide gripping members and a bridge like clamp for securing the clasp in position, said clamp being slotted for the passage therethrough of one of the gripping members, and having an outset tongue abutting 30 the clasp along the line of fold.

In testimony whereof I affix my signature.

JAMES C. HEEREY.
